FREEZER RACK

Richard T. Bussemer, Roslyn, Pa., assignor of one-third each to Paul London and Louis Griff, both of Philadelphia, Pa.

Filed Feb. 1, 1962, Ser. No. 170,598

3 Claims. (Cl. 211—134)

This invention relates to an article support, and more particularly, to a rack adapted to be utilized in freezers or other refrigerated apparatus wherein it is desired to provide a support for numerous small items.

When the article support of the present invention is utilized as a freezer rack, it may be disposed within a refrigerated compartment to support articles such as packages of frozen food or the like. The freezer rack of the present invention is an integrated structure providing a plurality of channels in parallel planes. One of the channels will be free from shelves. Each of the remaining channels will have one or more shelves disposed therein.

The freezer rack of the present invention is preferably made from wire having a non-toxic coating thereon which prevents or detracts from the ability of the articles to adhere to the rack. The parallel stacking channels are formed by closed substantially rectangular loops which are disposed in spaced upright parallel planes. A bottom tray and braces extending between adjacent loops are interconnected therewith to maintain the loops in assembled relationship. The rack of the present invention includes one channel which is unobstructed so that it may accommodate large packages. The remaining channels are provided with shelves so that the rack of the present invention may accommodate the various types and sizes of packages utilized commercially to package frozen foods and the like. The rack of the present invention facilitates storing packages of frozen articles in a more orderly and efficient fashion so that the articles may be readily removed from the rack when desired.

It is an object of the present invention to provide a novel article support.

It is another object of the present invention to provide a novel freezer rack.

It is another object of the present invention to provide a novel freezer rack which detracts from the tendency of the articles to adhere or become frozen to the rack.

It is another object of the present invention to provide a freezer rack which may be economically produced and efficiently support articles in a frozen compartment in an orderly manner.

It is another object of the present invention to provide a novel freezer rack which provides a plurality of channels for receiving packages of different sizes.

Other objects will appear hereinafter.

For the purpose of illustrating the invention there is shown in the drawings a form which is presently preferred; it being understood, however, that this invention is not limited to the precise arrangements and instrumentalities shown.

FIGURE 1 is a perspective view of the freezer rack of the present invention.

FIGURE 2 is a front elevation view of the freezer rack illustrated in FIGURE 1.

FIGURE 3 is a right end view of the rack illustrated in FIGURE 2.

FIGURE 4 is a transverse sectional view of a brace taken along the lines 4—4 in FIGURE 3.

Referring to the drawing in detail, wherein like numerals indicate like elements, there is shown in FIGURE 1 a freezer rack designated generally as 10.

The freezer rack 10 includes a plurality of substantially rectangular endless loops 12, 14, 16, 18 and 20. While five loops have been illustrated, it will be appreciated

2

that a larger or smaller number of loops may be utilized. The loops 12-20 are disposed in spaced substantially parallel planes. It will be noted that the substantially rectangular loops 12-20 have spaced parallel vertical upright portions 6 and 8 which are shorter than the horizontally disposed portions 2 and 4 connecting the lower and upper ends respectively of upright portions 6 and 8. The horizontally disposed portions of the loops correspond with the depth of the rack and the upright portions correspond with the height of the rack.

The entire rack 10 is made from wire as will be made clear hereinafter. The loops 12-20 may be made from wire as follows. Elongated strips of wire will be pre-cut to a predetermined length. The wires may be bent around a form so that the ends of the wires are juxtaposed to each other. Thereafter, the ends may be metallurgically joined by brazing, soldering, butt welding, etc.

The loops 12-20 are maintained in an upright disposition in spaced substantially parallel planes partially by a bottom tray 22. The bottom tray 22 includes spaced substantially parallel side runners 24 and 26. The runners 24 and 26 are in abutting contact with and fixedly secured to an inner surface of a horizontally disposed portion of the loops 12-20. In constructing the rack 10, I have secured the runners 24 and 26 to the loops 12-20 by spot welding overlapping portions. A plurality of struts 28 extend between and overlap the side runners 24 and 26. The struts 28 are preferably secured at their ends to the runners 24 and 26 by spot welding overlapping portions. It will be noted that the longitudinal axes of the struts 28 are parallel to the planes of the loops 12-20.

The struts 28 extend from front to rear on the rack 10. Hence, the struts appear as circles in a front elevation view of the rack 10, see FIGURE 2. The direction in which the struts 28 extend facilitates sliding packaged articles onto the rack 10 and removing the same.

A runner 30 is in abutting contact with and fixedly secured to an upright portion of each of the loops 12-20. The runner 30 is preferably fixedly secured to the loops 12-20 by spot welding overlapping portions. It will be noted that the longitudinal axis of the runner 30 is perpendicular to the planes of the loops 12-20. A runner 32 overlaps and is fixedly secured to an upright portion of the loops 14-20. The runners 30 and 32 cooperate with the bottom tray 22 to assist in maintaining the loops 12-20 in upright spaced planes.

The space above the bottom tray 22 and between adjacent loops constitute channels within which articles may be disposed. The channel between loops 18 and 20 is provided with two shelves disposed above the bottom tray 22. The first shelf includes a brace 34. The brace 34 extends between and is metallurgically joined to the upright portion of the loops 18 and 20. The brace 34 is parallel to and lies in the same horizontal plane as the runner 32. Struts 36 extend between the runner 32 and the brace 34. The ends of the struts 36 are metallurgically joined to overlapping portions of the runner 32 and brace 34.

The second shelf between the loops 18 and 20 is spaced from and overlies the first shelf. The second shelf includes a brace 38 extending between and fixedly secured to an upright portion of the loops 18 and 20. The ends of the brace 38 are preferably metallurgically joined to overlapping portions of the loops 18 and 20. The brace 38 is parallel to and lies in the same horizontal plane as the runner 30. Struts 40 extend between the runner 30 and brace 38. The ends of the struts 40 are preferably metallurgically joined to overlapping portions of the runner 30 and brace 38.

The space between loops 16 and 18 is preferably free from any shelves except for the shelf formed by the bot-

tom tray 22. This channel may be utilized to store large bulky items. For example, a one-half gallon package of ice cream may be disposed within the channel between loops 16 and 18.

A brace 42 extends across an upright portion of the loops 12-16 adjacent the front of the rack 10. A brace 44 extends across an upright portion of the loops 12-16 at the rear of the rack 10. The braces 42 and 44 are preferably metallurgically joined to overlapping portions of the loops 12-16. Struts 46 extend between the braces 42 and 44. The ends of the struts 46 are preferably metallurgically joined to overlapping portions of the braces 42 and 44.

Hence, it will be noted that the channel formed by loops 12 and 14 is provided with a shelf formed by the bottom tray 22 and a shelf formed by the braces 42 and 44. Similar shelves are provided between the loops 14 and 16. The width of the channel between the loops 14 and 16 is substantially identical with the width of the channel between loops 18 and 20. The width of the channel between loops 12 and 14 is substantially identical with the width of the channel between loops 16 and 18.

Struts 48 and 48' extend across upright portions of the loop 12. The struts 48 and 48' are on opposite sides of the shelf formed by the braces 42 and 44. Loop 14 is provided with struts 50 and 50' corresponding with the struts 48 and 48', respectively. The struts 48, 48', 50 and 50' prevent articles from shifting from one channel to the next adjacent channel.

The entire rack 10 is preferably made from a multi-layer wire material. For purposes of illustration, a sectional view of strut 46 is illustrated in FIGURE 4. It will be appreciated that all components of the rack 10 have a cross sectional view corresponding with the illustration in FIGURE 4. Hence, it will be noted that all components include a metal core 52 surrounded by a primer coat 54. The primer coat 54 may be any organic coating such as a latex primer coating. The primer coat 54 is surrounded by a layer of a vinyl resin. For example, the layer 56 may be a layer of polyvinyl chloride. The layers 54 and 56 may be applied in any conventional manner such as spraying, dipping, etc. The layer 56 prevents or reduces the tendency of the articles to adhere or become frozen to the rack 10.

The present invention may be embodied in other specific forms without departing from the spirit or essential attributes thereof and, accordingly, reference should be made to the appended claims, rather than to the foregoing specification as indicating the scope of the invention.

I claim:

1. A wire rack comprising first, second, third and fourth closed loops, said loops being substantially rectangular and being disposed in spaced parallel planes,

runners metallurgically bonded to the horizontal portion of each loop, a pair of spaced horizontal runners fixedly secured to an upright portion of each loop, a brace extending between an upright portion of said first and second loops at an end of said loops remote from said runners, a brace extending between an upright portion of said third and fourth loops at an end of said loops remote from said runners, struts extending between each brace and one of said runners to form a shelf between the first and second loops and between the third and fourth loops, and struts extending between the runners secured to a horizontal portion of each loop, said last mentioned struts having a longitudinal axis parallel to the planes of said loops, and the space between said second and third loops being free from any obstruction.

2. A rack in accordance with claim 1 wherein the loops, runners and struts are made from a wire core, said wire core being encased within a layer of polyvinyl chloride resin.

3. A freezer rack comprising a pair of spaced vertical parallel supports, said supports including first, second and third legs, said first and third legs being vertical, said second legs being horizontal and joining said first and third legs at the upper ends thereof, a first plurality of horizontal cross braces joining the first legs of said pair of vertical supports, said first plurality of cross braces being equally spaced along the length of said first legs, a second plurality of horizontal cross braces extending between the third legs of said pair of vertical supports, said second plurality of cross braces being spaced in horizontal planes corresponding to the horizontal planes of said first cross braces, and a plurality of pairs of shelf braces metallurgically bonded to each of said first and second cross braces in the same horizontal plane, said pairs of shelf braces being parallel to each other, one of each pair of shelf braces being connected between said cross braces one third of the distance between said parallel vertical supports and the other brace of each pair of shelf braces being connected two thirds of the distance between the spaced parallel vertical supports, and the supports, cross braces and shelf braces being made from a wire core, said wire core being encased within a layer of a vinyl resin.
